DESIGN FOR A TOY THEATER

Lawrence Wise, New York, N. Y., assignor to
Playette Corporation, New York, N. Y., a corporation of New York

Application December 15, 1942, Serial No. 109,040

Term of patent 7 years

(Cl. D34—15)

To all whom it may concern:

Be it known that I, Lawrence Wise, a citizen of the United States, residing at New York, in the county of Queens and State of New York, have invented a new, original, and ornamental Design for a Toy Theatre, of which the following is a specification, reference being had to the accompanying drawing, forming a part thereof.

Figure 1 is a view in perspective of my toy theater showing the front thereof and one of the sides; the left hand portion of the interior of the stage which is not visible in Figure 1 is similar to

and in symmetry with the portion of the right hand interior of the stage which is visible.

Figure 2 is a view in elevation on a reduced scale of the opposite side of the toy theater of Figure 1.

Figure 3 is a view in elevation on a reduced scale showing the rear of the toy theater of Figure 1.

I claim:

The ornamental design for a toy theater, as shown and described.

LAWRENCE WISE.
